Shackle for anchor or mooring weight. A shackle for anchor or mooring weight having a tubular bar with a crossbar and a cap, a triangular plate being slidably mounted in the bar, a spring being disposed within the bar, and a rod being slidably mounted within the bar and connected to the plate.

UNITED STATES PATENT OFFICE

2,574,859

MOORING SHACKLE

John Elmer Chisholm, Medford, Mass.

Application February 11, 1948, Serial No. 7,689

4 Claims. (Cl. 114—221)

1

This invention relates to a mooring shackle and its principal object is to provide a releasable shackle which can be inserted through and automatically locked to a loop member or ring carried by an anchor, weight or the like stationary member located on the floor of a harbor or anchorage, and which can be easily released or disengaged from the loop or ring by a simple manipulation of a control, without disturbing the anchor.

Further objects will be apparent from a consideration of the following description and the accompanying drawings, wherein:

Fig. 1 is an elevation, with parts broken away and shown in section, of a mooring shackle constructed in accordance with the present invention;

Fig. 2 is an elevation, as viewed from a position at right angles to Fig. 1;

Fig. 3 is an enlarged longitudinal sectional view;

Figs. 4 and 5 are sections on the lines 4—4 and 5—5, respectively, of Fig. 3; and

Fig. 6 is a view illustrating the manner of using the shackle.

The shackle S herein shown for the purpose of illustration comprises a tubular bar 1 which is screw-threaded at its ends 2 and 3 to receive a crossbar 4 and a cap 5, respectively. The crossbar 4 is formed adjacent to its opposite ends with openings 6 and 7 to provide means by which a mooring line or anchor chain 8 may be secured, as illustrated in Fig. 6, and the cap 5 is likewise provided with an opening 10 by means of which one end of a line 12 (Fig. 6) may be secured thereto.

The upper portion of the bar 1 is formed with diametrically disposed slots 14 and 15 and a generally triangular plate 16 is slidably mounted in the slotted portion with its opposite inner ends projecting laterally from the bar to provide lugs 17 and 18. Beneath the slotted portion the bar 1 carries a collar 20 having diametrically disposed projections, the upper surfaces of which are formed with grooves 21 (Fig. 3). An actuating rod or plunger 24 is slidably mounted within the upper end of the bar 1 and the inner end of this rod is connected to the plate 16. The upper end of the rod 24 projects outwardly beyond the crossbar 4 and carries a head 25 having an opening 26 by means of which either the opposite end of the line 12 or end of a control line 12a may be attached, as illustrated in Fig. 6.

A coil compression spring 28 is disposed within the upper end of the bar 1 so that one end acts on the plate 16 and its opposite end on a bushing

2

30 (Fig. 3) having a press fit within the bar 1. The spring 28 normally urges the plate 16 inwardly against the collar 20 but permits the plate to slide upwardly by pulling the rod 24.

The opposite end of the bar 1 is slotted to receive a small crossbar 32 the opposite ends of which project laterally from the bar 1 to provide fixed ears 33 and 34 contiguous to the flanged or shouldered inner end 35 of the cap 5. The corresponding ends of two pairs of diametrically disposed toggle links or members 36, 36a and 37, 37a are loosely pivoted to the lugs 17, 18 and the ears 33, 34, the construction and arrangement of parts being such that the toggle links are normally held in expanded position (Figs. 1 to 3), wherein they project laterally from the bar 1.

The pivotal connection between each pair of toggle links, as shown in Figs. 2 and 3, is sufficiently loose to permit stress to be borne by their 20 interengaging ends, rather than by the pivot pins, and likewise the loose pivotal connections between the links 36a, 37a and the ears 33, 34 are such that stress is borne by the flanged inner end 35 of the cap 5. The ends of the links 36 and 37 are formed with teeth 40 and 41 adapted to project into the grooves 21 of collar 20 when the links are swung to expanded position so that the strain exerted on the links is borne by the collar rather than the adjacent pivot pins.

When the rod 24 is pulled outwardly against the action of the spring 28, the links are collapsed or retracted, as illustrated by the dot-and-dash lines of Fig. 1, so that the bar 1, links and associated parts may be passed through the looped portion or eye 45 of a swivel shackle member secured to an anchor or mooring weight; and when the rod 24 is released, the spring 28 retracts the rod and expands the links so as to prevent the bar 1, links and associated parts from being withdrawn through the eye 45, as illustrated by the full lines of Fig. 1, it being noted that tension exerted by the anchor chain 8 on the crossbar 4 is ineffective to collapse the links.

In use the shackle S is first inserted through 45 the eye 45 of a mooring weight or anchor A, as shown in Fig. 6, and the anchor chain 8 and control lines 12 and 12a may then be attached to the crossbar 4, cap 5 and head 25, respectively, after which the mooring weight or anchor and assembled parts may be dropped overboard into a harbor or anchorage. After the anchor has been positioned, the opposite ends of the anchor chain 8 and control lines 12 and 12a are attached to a buoy in the usual manner. The shackle S may be unlocked or disengaged from the anchor with-

50

out disturbing the latter by slackening off on the line 12 and hauling in on the line 12a which collapses the links so as to permit the bar 1 to be drawn through the eye 45 along with the line 12. To return and lock the shackle to the eye 45 it is merely necessary to haul in on the line 12, the pressure of the eye 45 on the links 36a, 37a being effective to collapse them so that the shackle may be drawn through the eye, after which the spring 28 urges the links to expanded or locking position.

While I have shown and described one desirable embodiment of the invention it is understood that this disclosure is for the purpose of illustration and that various changes and modifications may be made therein without departing from the spirit and scope of the appended claims.

I claim:

1. A mooring shackle comprising an elongate bar having means by which it may be secured to a mooring line; a locking member pivotally mounted on said bar so as to swing inwardly relative to said bar from a normally locking position, wherein said bar and locking member engages a loop member of predetermined size to prevent said bar and locking member from passing through said loop member, to a collapsed position, wherein said bar and locking member may be passed through the loop member; means yieldingly holding said locking member in locking position; and means connected to said locking member and attachable to a control line for collapsing said locking member so that said bar and locking member may be drawn through and disengaged from the loop member.

2. A mooring shackle comprising an elongate bar having means by which it may be secured to a mooring line; a lug slidably longitudinally of said bar; toggle links, one of which is pivotally connected to said bar, and the other of which is pivotally connected to said lug; resilient means acting on said lug so as yieldingly to hold said links in a normally locking position, wherein one of said links engages a loop member of predetermined size to prevent said bar, lug and links from passing through the loop member, to a collapsed position, wherein said bar, lug and links may be passed through said loop member; and means connected with said lug and attachable to a control line for sliding said lug longitudinally of said bar, thereby to collapse said links so that said bar, lugs, and links may be drawn through and disengaged from the loop member.

5
10

3. A mooring shackle comprising an elongate bar having means by which it may be secured to a mooring line; a member having diametrically disposed lugs slidable longitudinally of said bar; two pairs of diametrically disposed toggle links, the corresponding links of each pair being pivotally connected with said lugs and with said bar adjacent to one end thereof; resilient means acting on said lugs so as yieldingly to hold said links in a normally locking position, wherein one of the links of each pair engages a loop member of predetermined size to prevent said bar, lugs and links from passing through the loop member, to a collapsed position, wherein said bar, lugs and links may be passed through said loop member; and means connected with said lugs and attachable to a control line for sliding said lugs longitudinally of said bar, thereby to collapse said links so that said bar, lugs and links may be drawn through and disengaged from a loop member.

4. A mooring shackle comprising an elongate, tubular bar having means at one end by which it may be secured to a mooring line and means at its opposite end by which it may be attached to one end of a control line; said one end having a longitudinally slotted portion; lugs slidably mounted in said slotted portion and having parts projecting laterally from said bar; two pairs of diametrically disposed toggle links, the corresponding ends of said links being pivotally connected with said lugs and with said bar adjacent to said opposite end; a helical spring disposed within said bar so as to act on said lugs yieldingly to hold said links in normally locking position, wherein the corresponding links of each pair engage a loop member of predetermined size to prevent said bar, lugs and links from passing through the loop member, to a collapsed position, wherein said bar, lugs and links may be passed through the loop member; and a rod positioned within said bar and secured at its inner end to said lugs, the outer end of said rod projecting outwardly beyond said one end and having means by which it is attachable to the end of a second control line so that when pulled outwardly it collapses said links to permit said bars, lugs and links to be drawn through and disengaged from the loop member.
